No. 36,802.

Patented February 16, 1904.

UNITED STATES PATENT OFFICE.

LOUIS SEPULCHRE, OF HERSTAL, BELGIUM.

DESIGN FOR A CHIMNEY-REFLECTOR FOR LAMPS.

SPECIFICATION forming part of Design No. 36,802, dated February 16, 1904.

Application filed August 4, 1902. Serial No. 118,412. Term of patent 14 years.

To all whom it may concern:

Be it known that I, LOUIS SEPULCHRE, manufacturer, a subject of the King of Belgium, residing at 267 Rue St. Lambert, Herstal-lez-Liège, Belgium, have invented a new, original, and ornamental Design for a Chimney-Reflector for Lamps, of which the following is a specification.

In the drawings, Figure 1 is a perspective

view of a chimney-reflector embodying my design, and Fig. 2 is a plan view of the same.

What I claim is—

The ornamental design for a chimney-reflector for lamps shown.

LOUIS SEPULCHRE.
